UNITED STATES PATENT OFFICE.

JOHN J. HALLORAN, OF DALY CITY, CALIFORNIA.

DESIGN FOR A RADIATOR-CAP.

58,292.

Specification for Design.

Patented July 5, 1921.

Application filed March 22, 1921. Serial No. 454,487. Term of patent 3½ years.

To all whom it may concern:

Be it known that I, JOHN J. HALLORAN, a citizen of the United States, residing at Daly City, county of San Mateo, in the State of California, have invented a new, original, and ornamental Design for a Radiator-Cap, of which the following is a specification, reference being had to the accompanying drawing, forming a part thereof.

Figure 1 is a perspective view of a radiator cap showing my new design.

Fig. 2 is a top plan view thereof.

I claim:

The ornamental design for a radiator cap as shown.

JOHN J. HALLORAN.

Witness:

ALEXANDER S. BLANC.
